UNITED STATES PATENT OFFICE.

JOEL SIGEL GOSS, OF OCEANPARK, AND CHARLES JEFFERSON WILSON, OF LOS ANGELES,
CALIFORNIA.

POWER-WHEEL.

1,120,930.

Specification of Letters Patent. Patented Dec. 15, 1914.

Application filed February 7, 1914. Serial No. 817,265.

To all whom it may concern:

Be it known that we, JOEL SIGEL Goss and CHARLES JEFFERSON WILSON, citizens of the United States, residing at Oceanpark, county of Los Angeles, State of California, and the city of Los Angeles, county of Los Angeles, State of California, respectively, have invented a new and useful Power-Wheel, of which the following is a specification.

Our invention relates to a turbine which being submerged below the surface of the waves, and where acted upon by the undertow and waves will produce rotary motion.

The objects of our invention are first, to provide continuous motion by single turbines or to connect the same in series by belts, and second to commercialize this motion in producing power.

We attain these objects by the mechanism illustrated in the accompanying drawings.

Figure 1, is a cross section of the turbine on line *e* of Fig. 2. Fig. 2, is a side elevation showing a pulley on the shaft. Fig. 25 4, is an enlarged blade in cross section. Fig. 5, is an enlarged elevation of blade *a*.

We prefer to construct our invention of sheets of metal *g* and *h* for bottom and top plates, spaced a suitable distance apart between which metal blades *a* are riveted or bolted to each other and blades *b*, to partition plates *c* and to bottom and top plates *g* and *h*.

This turbine is to be operated by being suspended in the ocean and just above the bed so as to receive the action of the undertow and waves. The shaft is to be held in

a vertical position by being passed through two shaft bearings, one near the turbine and one at some distance above near the pulley 40 *d*. Pulleys one of which is shown at *d* are to be fastened to the shaft on each side of the shaft bearings and secured to the shaft by set screws. The turbine being thus held in position and secured against lateral or 45 vertical motion by being secured to the shaft and held firmly by the shaft bearings and collars, will be acted upon by the force of the undertow and waves, from any direction, and caused to rotate about its axis in 50 a positive direction. A belt may be passed over the pulley *d* and the power transmitted to any desired point.

We claim:

1. An ocean power wheel of a turbine 55 type comprising in combination, bottom and top plates, *g* and *h* at right angles to and secured to a shaft carrying pulley, *d*; partition *c* spaced about the shaft; curved blades, *a* fastened at right angles to plates *g* and *h* 60 and to partition *c* to form in cross-section a square about said shaft; and curved blades, *b* secured at right angles to plates, *g* and *h* and to partitions *c*.

2. The combination of a series of blades, 65 *a*; partitions *c*; and top and bottom plates *g* and *h* forming water tight compartments open at the periphery of the wheel.

JOEL SIGEL GOSS.

CHARLES JEFFERSON WILSON.
